D 532

OR D 15,099

No. 15,099

June 24, 1884

UNITED STATES PATENT OFFICE.

MARTIAL REDON, OF LIMOGES, FRANCE, ASSIGNOR TO A. KLINGENBERG,
OF NEW YORK, N. Y.

DESIGN FOR TABLE-WARE.

SPECIFICATION forming part of Design No. 15,099, dated June 24, 1884.

Application filed April 2, 1884. Term of patent 7 years.

To all whom it may concern:

Be it known that I, MARTIAL REDON, a citizen of the Republie of France, and a resident of Limoges, France, have invented or produced a new and original Design for Table-Ware, of which the following is a specification.

My design relates, in general, to dishes, and particularly to the several pieces that constitute table and toilet sets. I have selected the soup-tureen from the several pieces constituting a dinner-set, as that embodies all the novel features of my design.

Figure 1 of the accompanying photograph is a plan or top view of a soup-tureen embodying my design, and Fig. 2 is a perspective view of the side of same.

The body *A* of the dish, when viewed in plan, has slightly convex sides and rounded corners. The body flares upward to near the top and then contracts. The lower flared portion of the body *a* is ornamented in imitation of wicker or basket work, which ornamentation extends from the base up to the largest part, and terminates at both top and bottom with a border, *a'*, in imitation of wrapped willow or wicker work. These borders are horizontal and parallel with each other. The contracted upper portion, *b*, of the body is plain and without ornament. The handles *c* at the ends of the body are made each to represent two rustic stems crossed by a third stem. The stems which project from the dish are inclined upward, and have a reverse curvature. The cover *B* of the dish conforms in plan to the shape of the body, projects somewhat beyond the contracted top of body, and has the form of a flattened cone. The central part of the cover is ornamented with a design, *d*, in imitation of wicker-work, similar to the body, this ornamented portion having substantially the same contour as the cover, and having a border, *d'*, in imitation of wrapped willow-work, similar to *a'* on the body. The margin *e* of the cover is plain and unornamented. The handle *f* on the cover is formed of two rustic stems, which project obliquely from the

cover, and a third rustic stem, which rests between the inner faces of the upright stems.

I am aware that designs for table-ware have been before produced showing an imitation of wicker or basket work at the base of the dish or vessel, and I do not claim this, broadly; nor do I claim, broadly, as a design for a handle of a dish three crossed rustic stems, as this, broadly, is not new with me.

Having thus described my invention, I claim—

1. A design for dishes, comprising the ornamentation *a*, in imitation of wicker or basket work, on the flared lower portion of the body, and the borders *a'*, in imitation of wrapped willow or wicker work, arranged at the upper and lower margins of the ornamentation *a*, said borders being parallel with each other and horizontal, and the upper part of the body left plain, substantially as shown in the accompanying photograph.

2. A design for a dish-cover, comprising the ornamentation *d* of the cover, in imitation of wicker or basket work, a border, *d'*, in imitation of wrapped willow-work, around the ornamentation *d*, and a plain marginal band, *e*, of equal width throughout, exterior to the border *d'*, substantially as shown in the accompanying photograph.

3. A design for a dish-handle, *c*, comprising a representation of two rustic stems, which are inclined upward and have a reverse curvature, and are crossed by a third rustic stem, as shown in the accompanying photograph.

4. A design for a handle, *f*, of a dish-cover, comprising the representation of two obliquely-projecting rustic stems, and a third rustic stem arranged crosswise between the two obliquely-projecting stems, substantially as shown in the accompanying photograph.

In witness whereof I have hereunto signed my name in the presence of two subscribing witnesses.

MARTIAL REDON.

Witnesses:

JOSEPH DU MURAUD,
ALBERT DETJINS.
